UNITED STATES PATENT OFFICE.

EDWARD J. QUIGLEY, OF NEW YORK, N. Y.

COMBINATION-GARMENT.

1,141,486.

Specification of Letters Patent. Patented June 1, 1915.

Application filed March 21, 1914. Serial No. 826,218.

To all whom it may concern:

Be it known that I, EDWARD J. QUIGLEY, a citizen of the United States, and a resident of New York city, county and State of New York, have invented certain new and useful Improvements in Combination-Garments, of which the following is a specification.

This invention relates to combination garments, and the objects of the invention are 10 to make a combination garment that is easy to put on or take off and can be made either as underwear or as a shirt with drawers attached.

Further objects of the invention are to 15 improve the back of the garment.

To the accomplishment of the above objects and to such others as may hereinafter appear the invention comprises a combination garment having shirt and drawers suitably united and open in a straight line from 20 the neck to the vicinity of the waist line, at which point the front portions of the garment are cut laterally in both directions, the front portions of the garment overlapping 25 the front portion of the drawers.

The invention further comprises a back which is cut on a line from the back of the drawers to the inner side of one of the drawer legs.

30 In the drawings: Figure 1 is a front view of a garment made in accordance with the invention. Fig. 2 is a garment shown in Fig. 1 in open position. Fig. 3 is a back view of a garment made in accordance with 35 the invention. Fig. 4 is the garment shown in Fig. 3 in open position.

Referring to the drawings, 1 designates the body of an undergarment, or union suit, to which is secured the drawers 2, in 40 the present instance shown as of knee length, although the same may be made longer if so desired.

The body 1 is open down the front, as shown at 3, the opening extending from the 45 neck to the vicinity of the waist line of the garment. The front portions 4 of the garment, that form the opening 3, are cut in a straight line from the neck to the vicinity of the waist line, at which point the front 50 portions 4 are cut laterally in both directions to the points 5, to permit of the garment being opened as shown in Fig. 2.

The front portion 6 of the drawers 2 is arranged to be overlapped by the front portions 4 of the garment and closed by means 55 of buttons 7, as shown in Fig. 1, similar

buttons 8 being provided for closing the front opening 3.

The front portion 6 of the drawers is also provided with an opening 9 which, in the 60 present instance, does not extend upward to the top of the front portion 6.

From the above description it will be seen that the garment, shown in Figs. 1 and 2, when open, affords a very large opening to 65 facilitate the garment being put on or taken off. It will also be seen that this construction does not necessitate the front of the drawers being open to the waist line, the same being preferably closed at the top to 70 facilitate the closing and fit of the garment.

The front portions 4 are preferably cut and attached to the front of the drawers so as to overlap the same when closed as shown in Fig. 1. This underlapping of the front 75 portion of the drawers permits of the garment being opened by unfastening only one of the buttons 7, without unfastening the other button 7.

In the case of a stout person this construction permits of the buttons 7 being set more nearly to the top of the drawers, without altering the garment otherwise so as to lengthen the front of the garment.

In Figs. 3 and 4 is shown the back of the 80 garment, which can be applied to any form of garment of the union type, which is open on a line 10 from the point 11 at the back of the drawers, to the point 12 at the inner side of one of the drawer legs, the opening 90 being closed by means of buttons 13 or other suitable means. When the back is unbuttoned the same can be folded back, as shown in Fig. 4, affording a very large opening 95 that is very conveniently opened or closed.

While the invention has been described with particular reference to an undergarment, it is obvious that the body of the garment can be made in the form of a dress or negligée shirt with drawers attached.

100 While the invention has been described with particular reference to the details of construction, the same is not to be considered as limited thereto, as many changes can be made and still fall within the scope of the 105 invention set forth in the following claims.

What I claim is:

1. A combination garment comprising a one-piece suit, consisting of shirt and drawers combined, the front of said shirt being 110 cut on a straight line from the neck to the vicinity of the waist line, and thence later-

ally in both directions to a mid-point on the outside of the drawers, thereby forming two flaps which may be turned backward laterally from the neck to the drawers, the lower ends of said flaps being arranged to overlap the front of said drawers, and means for buttoning said flaps together, and to the front of said drawers.

2. A combination garment comprising a one-piece suit, consisting of shirt and drawers combined, the back of said drawers, com-

prising the seat, being cut on a line starting from a mid-point in the back to the inner side of the bottom of one of the drawer legs.

In testimony whereof I have signed this 10 specification in the presence of two subscribing witnesses.

EDWARD J. QUIGLEY.
